UNITED STATES PATENT OFFICE

169,827

CARVING AID FORK

Joseph Schoenfeld, San Diego, Calif.

Application February 13, 1953, Serial No. 23,601

Term of patent 14 years

(Cl. D44—29)

To all whom it may concern:

Be it known that I, Joseph Schoenfeld, a citizen of the United States and a resident of San Diego, county of San Diego, State of California, have invented a new, original, and ornamental Design for a Carving Aid Fork, of which the following is a specification, reference being had to the accompanying drawing, forming a part thereof.

Figure 1 is a top view of a carving aid fork showing my new design;

Figure 2 is a side elevation thereof; and

Figure 3 is a front elevation thereof.

I claim:
The ornamental design for a carving aid fork, as shown.

JOSEPH SCHOENFELD.
